(57) **CLAIM**

The ornamental design for a collapsible water tank, as shown and described.

DESCRIPTION

FIG. 1 is an isometric view of an embodiment of a collapsible water tank with a lid;

FIG. 2 is a front view of the collapsible water tank of FIG. 1; FIG. 3 is a rear view of the collapsible water tank of FIG. 1; FIG. 4 is a left-side view of the collapsible water tank of FIG. 1;

FIG. 5 is a right-side view of the collapsible water tank of FIG. 1;

FIG. 6 is a top view of the collapsible water tank of FIG. 1; and,

FIG. 7 is a bottom view of the collapsible water tank of FIG. 1.

The broken line showing is included for the purpose of illustrating and forms no part of the claimed design.
